US00D528173S

(12) **United States Design Patent** (10) Patent No.: **US D528,173 S**
Flick et al. (45) Date of Patent: **** Sep. 12, 2006**

- (54) **ADJUSTABLE DUMBBELL BASE**
(75) Inventors: **Edward L. Flick**, Denver, CO (US);
Eric D. Golesh, Thornton, CO (US)
(73) Assignee: **Nautilus, Inc.**, Vancouver, WA (US)
(***) Term: **14 Years**
(21) Appl. No.: **29/211,519**
(22) Filed: **Aug. 16, 2004**

Related U.S. Application Data

- (63) Continuation of application No. 10/456,977, filed on Jun. 5, 2003.

(74) Attorney, Agent, or Firm—Dorsey & Whitney LLP

(57) **CLAIM**

The ornamental design for an adjustable dumbbell base, as shown and described.

DESCRIPTION

FIG. 1 is an isometric view of the adjustable dumbbell base in accordance with the present invention;
FIG. 2 is a front elevation view thereof;
FIG. 3 is a rear elevation view thereof;
FIG. 4 is a top plan view thereof;
FIG. 5 is a right side elevation view thereof;
FIG. 6 is a left side elevation view thereof;
FIG. 7 is a bottom plan view thereof; and,
FIG. 8 is an isometric view of the adjustable dumbbell base, wherein the broken line showing of the adjustable dumbbell is for illustrative purposes only and forms no part of the claimed design.
